UNITED STATES PATENT OFFICE.

MICHAEL FUNK, OF LA CROSSE, WISCONSIN.

FEED-WATER HEATER.

SPECIFICATION forming part of Letters Patent No. 317,636, dated May 12, 1885.

Application filed January 14, 1885. (No model.)

To all whom it may concern:

Be it known that I, MICHAEL FUNK, a citizen of the United States, residing at La Crosse, in the county of La Crosse and State of Wisconsin, have invented certain new and useful Improvements in Feed-Water Heaters, of which the following is a specification, reference being had therein to the accompanying drawings.

10 This invention has relation to improvements in feed-water heaters; and it consists in the construction and novel arrangement of devices, as will be hereinafter fully explained, and particularly pointed out in the appended 15 claims.

The annexed drawings, to which reference is made, fully illustrate my invention, in which Figure 1 represents a vertical sectional view, and Fig. 2 is a detail sectional view of 20 the same.

Referring by letter to the accompanying drawings, A designates the outer shell or jacket, having the inlet-port *a* at the bottom thereof for the passage of the exhaust-steam 25 from an engine and the outlet-port *b* for the escape of the same, and in one side of said jacket is provided an opening, *c*, surrounded on its outer side with a flange, *d*, that receives a removable cap, *e*, whereby said opening is 30 closed. This hole permits of the hand being passed within the shell or jacket, in order that the interior thereof may be readily cleaned.

B represents the inner cylinder or water-receptacle, which latter enters the lower portion thereof through a connecting-pipe, *f*, with the same and the outer cylinder or jacket, having suitable packing-boxes, as shown, and at the upper portion of said water-chamber is the outlet-pipe, also having a similar 40 connection with the outer shell. Said shell or jacket is provided on its top plate with an opening, *g*, which is covered by a plate, *h*, screwed securely thereto by the bolts *i*, and which also serves as a hand-hole for the interior 45 of the heater or space surrounding the same. If desirable, two or more of the hand-holes in the side of the outer jacket may be provided.

The inner shell or water-heater consists of the cylinder portion, which extends from the 50 bottom plate of the outer casing nearly to the top plate thereof, having a space between the

top plate of the same and the top of said jacket. Said top and bottom plates of the inner cylinder are provided with marginal flanges *j*, which are perforated to receive rivets, by which they are secured to said cylinder. The plates are also provided with openings *k*, which have marginal flanges *l*, by means of which the flues *m* are riveted thereto. 55

Below the bottom plate, and between the same and the lower plate of the outer casing, is a space, *n*, which communicates with the flues and provides a passage for the steam from the inlet-pipe. Said space is surrounded by the lower edge of the inner cylinder, forming an inclosure, and upon which said cylinder is supported, resting upon the lower plate of the outer cylinder or casing, as shown in the drawings. 65

The heater is provided with the usual drip-pipe and blow-pipe, of any approved construction. 70

It will be seen by reference to the annexed drawings that the upper and lower ends of the flues are riveted to the flanges on the top and bottom of the inner cylinder, thus preventing leakage by contraction and expansion at these points; also, the flues being large, (about six inches in diameter,) permits a greater heating-surface and a free circulation of the exhaust-steam from the engine and relieving the steam from back-pressure, at the same time providing ample room between said flues to remove 80 all scales and impurities that accumulate from the feed-water in the heater, which removal is accomplished through the hand-hole, which cannot be done in heaters having small flues or tubes, and by providing the large flues with thick material the same will not corrode as quickly as smaller flues. 85

Having described my invention, what I claim, and desire to secure by Letters Patent, is—

1. The feed-water heater herein described, consisting of the outer casing, A, having the openings *c* in its vertical wall near the bottom thereof and arranged directly opposite the opening in the inner casing, and the inner casing, B, constructed as shown, said outer casing provided with the flange *d*, encircling the opening *c*, having the exterior screw-threads to engage interior threads in the cap 95 100

e, whereby access may be had to the inner cylinder at its lower end, as and for the purposes set forth.

2. In an upright feed-water heater, the combination, with the outer casing, constructed as shown, of the inner cylinder having at its lower end the opening directly opposite the opening *c* in the outer casing, and provided at its top and bottom with the plates of similar construction, having the outer flange to engage the inner wall of the inner cylinder, which is secured thereto, and each having the openings to receive the upper and lower ends of the flues *m*, said openings surrounded by the marginal flange *l*, whereby said flues are secured to the plates by bolts passing through the flange and flue, the whole arranged as shown and described.

3. In a feed-water heater of the class herein shown, the combination, with the outer cylinder or casing, constructed as described, of the

inner cylinder, *B*, provided with the flues *m* and the opening, and the upper and lower plates having the flanged openings to receive the flues and marginal flange, whereby said plates are secured to the inner cylinder by bolts, as shown, the lower plate arranged within the lower portion of said inner cylinder to form a passage between the same and the bottom plate of the outer casing, the lower marginal edge of the inner cylinder serving as a support for the latter, and an inclosing wall for the space between the bottom of the inner cylinder and outer casing, the whole arranged as shown and described.

In testimony whereof I affix my signature in presence of two witnesses.

MICHAEL FUNK.
